UNITED STATES PATENT OFFICE.

ELIJAH L. JOHNSON, OF LOS ANGELES, CALIFORNIA.

DESIGN FOR BUTTER-TONGS.

45,533.

Specification for Design.

Patented Mar. 31, 1914.

Application filed February 17, 1913. Serial No. 749,049. Term of patent 14 years.

To all whom it may concern:

Be it known that I, ELIJAH L. JOHNSON, a citizen of the United States, residing at Los Angeles, in the county of Los Angeles and State of California, have invented a new, original, and ornamental Design for Butter-Tongs, of which the following is a specification, reference being had to the accompanying drawing, forming part thereof.

Figure 1 is a perspective view of my im-

proved butter tong. Fig. 2 is a side elevation of the tong.

I claim:

The ornamental design for a butter tong as shown.

ELIJAH L. JOHNSON.

Witnesses:

EDMUND A. STRAUSE,
MARIE BATTEY.
